(57) **CLAIM**

The ornamental design for a mug, as shown and described.

DESCRIPTION

FIG. 1 is a perspective view of our mug taken from the top left thereof;

FIG. 2 is a perspective view of our mug taken from the bottom right thereof;

FIG. 3 is a front side elevation of our mug;

FIG. 4 is a rear side elevation of our mug;

FIG. 5 is a right side elevation of our mug, it being understood that a left side elevation is a mirror image of this figure;

FIG. 6 is a plan view of our mug; and,

FIG. 7 is a bottom view of our mug.
